GAS METER VALVE WRENCH

Joseph C. Bloom, 1815 Guerneville Road,
Santa Rosa, Calif. 95406

Filed Sept. 19, 1973, Ser. No. 398,824

Term of patent 7 years

Int. Cl. D8—05

U.S. Cl. D8—17

FIG_1

FIG_5

FIG_2

FIG_3

FIG_4

FIG. 1 is a perspective view of a gas meter valve wrench showing my new design;

FIG. 2 is a top plan view thereof;

FIG. 3 is a side elevational view thereof, both side elevational views being the same;

FIG. 4 is a bottom plan view thereof; and

FIG. 5 is an end elevational view thereof, both end elevational views being the same.

I claim:

The ornamental design for a gas meter valve wrench, substantially as shown and described.
